UNITED STATES PATENT OFFICE

159,818

WHEEL COVER OR SIMILAR ARTICLE

George Albert Lyon, Detroit, Mich.

Application May 25, 1948, Serial No. 146,584

Term of patent 14 years

(Cl. D14—30)

To all whom it may concern:

Be it known that I, George Albert Lyon, a citizen of the United States and a resident of the city of Detroit, in the county of Wayne and State of Michigan, have invented a new, original, and ornamental Design for a Wheel Cover or Similar Article, of which the following is a specification, reference being had to the accompanying drawing, forming a part thereof.

On the drawing:

Figure 1 is a side view of my novel design for a wheel cover or similar article;

Figure 2 is a profile view showing in outline form the diametric cross sectional contour of the wheel cover illustrated in Figure 1; and

Figure 3 is a fragmentary sectional perspective view of the wheel cover.

I claim:

The ornamental design for a wheel cover or similar article, substantially as shown.

GEORGE ALBERT LYON.
